Primary Examiner — Austin Murphy(74) *Attorney, Agent, or Firm* — Cantor Colburn LLP(57) **CLAIM**

The ornamental design for a hard surface cleaning device, as shown and described.

DESCRIPTION

FIG. 1 is a first top perspective view of a hard surface cleaning device according to the present disclosure;

FIG. 2 is a second top perspective view of the hard surface cleaning device of FIG. 1;

FIG. 3 is a first bottom perspective view of the hard surface cleaning device of FIG. 1;

FIG. 4 is a second bottom perspective view of the hard surface cleaning device of FIG. 1;

FIG. 5 is a front view of the hard surface cleaning device of FIG. 1;

FIG. 6 is a rear view of the hard surface cleaning device of FIG. 1;

FIG. 7 is a first side view of the hard surface cleaning device of FIG. 1;

FIG. 8 is a second, opposite side view of the hard surface cleaning device of FIG. 1;

FIG. 9 is a top view of the hard surface cleaning device of FIG. 1; and,

FIG. 10 is a bottom view of the hard surface cleaning device of FIG. 1.

The broken lines in the figures form no part of the claimed design.
